UNITED STATES PATENT OFFICE.

ROBERT Y. BARROWS, OF RUTHERFORD, NEW JERSEY, ASSIGNOR TO ROBERT Y. BARROWS, INC., A CORPORATION OF NEW YORK.

PHONOGRAPH.

Application filed July 14, 1921. Serial No. 484,540.

The invention relates to phonographs or talking machines. An object of the invention is the provision of an apparatus which will give an improved tone or quality of ⁵ production, which will occupy less space and be less expensive to manufacture than other types of high grade apparatus in common use. Other features of the invention comprise novel combinations of parts and ¹⁰ proved details of construction, all as will be more fully described in the following specification and particularly pointed out in the appended claims.

As a result of study and experimentation ¹⁵ I have discovered that the amplifying horn as usually constructed and used tapers too sharply to permit a proper expansion of the sound vibrations or impulses, and produces an increase of power by reflection in the same ²⁰ manner as does a megaphone. In the preferred form of the invention the sound vibrations generated in the sound box by the movement of the diaphragm therein are delivered to a large area of the free air of the room by ²⁵ means of a thin membrane or diaphragm which is fixed across a shallow recess or thin air chamber, the interior of which is in communication with that of the sound box.

³⁰ Although the large membrane or diaphragm referred to offers but slight resistance to the sound vibrations, it is apparently sufficient to cause them to be distributed over the whole interior of the air chamber, ³⁵ whereupon they are imparted to the free air of the room over a large area.

It will thus be noted that I obviate the effects resulting from the use of a horn or amplifier having a considerable taper by ⁴⁰ means of a construction in which no horn or similar tapered body is used, the present construction operating in accordance with a quite different principle. Further and more specific objects and advantages will more ⁴⁵ clearly appear from the detailed description given below.

In order that the invention may be more clearly understood attention is hereby directed to the accompanying drawings forming part of this application and illustrating, by way of example, certain embodiments of the invention.

In the drawings:—

⁵⁰ Fig. 1 represents a view partly in front elevation and partly in vertical section of a

form of construction embodying the invention;

Fig. 2 is a vertical section taken on line 2—2 of Fig. 1;

Fig. 3 is a horizontal section taken on line 3—3 of Fig. 1;

Fig. 4 is a detail vertical section taken through the cover and the connection of the tone arm with the amplifying recess;

Fig. 5 is a vertical section taken on line 5—5 of Fig. 4; and

Fig. 6 is a vertical section through a modified form of construction.

Referring first to Figs. 1 to 5 of the drawings, a casing 1 is illustrated, preferably supported on legs 2. A motor 3 of any desired construction is indicated as carried by a frame 4, preferably at one end of the casing. The record support is provided, in the construction illustrated, by the turn table 5 ⁷⁰ ⁷⁵ on which the record indicated at 6 may be placed, the turn table being mounted on the vertical spindle 7 for rotation by the motor in the usual manner.

The cover 8 is preferably hinged to the ⁸⁰ rear upper edge of casing 1 by suitable hinges, such as the hinge indicated at 9, in Fig. 4. The cover is adapted to close down over casing 1 when the turn table 5 has been removed from position on spindle 7 and the sound box ⁸⁵ and tone arm suitably secured to the cover, as will be described. When the cover is in its open position, as shown in the drawings, it may be held in such position by means of a brace 10 adapted to extend diagonally from ⁹⁰ a side of the casing to a side of the cover and be secured in such position by means of thumb nut 10^a.

Cover 8 is provided with an air chamber, or recess 11, which preferably takes the form ⁹⁵ of a thin rectangular enclosure. The front of this enclosure is covered by a diaphragm 12 while the back and sides of the recess or air chamber are closed by the heavy wooden portions of the cover construction, with the ¹⁰⁰ exception of an opening at one point by which connection is made with the sound box.

A sound box 13, provided with the usual diaphragm and with a reproducing stylus ¹⁰⁵ 14 is carried by the tone arm or sound conduit 15, by which connection is established between the sound box and the air chamber 11.

¹¹⁰ The large diaphragm 12 may be a thin

membrane of paper, cloth, or other suitable material. It should be light in weight, and more or less air tight, and should be preferably fixed in place to lie flat but not too tightly stretched, since in that case it will offer too much resistance. I have found that the linen which is treated to make the same air tight for the purpose of forming window shades is very well adapted for this purpose.

I have illustrated diaphragm 12 as secured to a frame 16 which may be secured to, or formed integral with the cover 8, the sides of this frame preferably being parallel to the outside flanges 17 of the cover member, which are adapted to seat against the upper edges of casing 1. The diaphragm or membrane 12 may be secured in position on the frame 16 by suitable means such as a thin strip 18 positioned thereon and secured to the frame 16 along the edge of the membrane 12 by suitable screws 19, or the like.

I have found it desirable that the air space within chamber 11 should be comparatively thin in order that the force of the vibrations transmitted from the diaphragm of the sound box to the diaphragm 12 should be conserved. By way of example I may state that I have found a distance of one-half inch between the back of the air chamber and the diaphragm 12 to be sufficient and to give good results when the diaphragm 12 has a surface area of 200 square inches or less.

It is desirable that the back of the air chamber 11 as well as the sides thereof, formed by frame 16, should be of comparatively hard and non-resilient material, in order that the membrane 12 should receive the full force of the vibrations. The cover 8 and frame 16 may suitably be formed of wood.

When a disc record is reproduced, as is indicated in the drawings, the tone arm, or connecting arm 15, must, of course, be so connected with the cover as to enable the stylus to travel across the record and also to be lifted therefrom. I have illustrated a form of tone arm connection which is suitable for the purpose and which constitutes one of the features of the invention.

As shown, a hollow bracket 20 is secured to cover member 8 to extend forwardly therefrom when the cover is in rest position, the rear end of this hollow bracket communicating with the lower end of air chamber 11 below the membrane 12. The bracket or fixed conduit member 20 is provided at its forward end with upwardly extending tubular portion 21, the upper edge of which is rounded, as shown at 22. The tone arm or movable conduit member 15 is provided at its end distant from the sound box with a downwardly turned extension 23, formed

with a bearing surface 24 adapted to rest on the rounded upper edge 22 of tubular portion 21. The bearing surface 24 is preferably formed as a segment of a sphere, the center of which may be located in the lower portion of bracket 20.

The upwardly extending tubular portion 21 of bracket 20 is preferably provided with a chase or groove 25 extending peripherally about its outer surface. The downward extension 23 of tone arm 15 continues, below the bearing surface 24, as a tubular flange 26 surrounding the upper part of the tubular portion 21 of bracket 20, the inside diameter of flange 26 being greater than the outside diameter of tubular portion 21. A pair of lugs extend inwardly from the sleeve portion 26 into the chase 25 at diametrically opposite points so as to prevent side rocking of the tone arm when a record is being reproduced, these two lugs preferably taking the form of screws 27 which are adjustably mounted in sleeve portion 26 of the tone arm to engage against the upper horizontal surface of chase 25, as is shown in Fig. 5.

With this arrangement the tone arm may, of course, swing about bracket 20 in a horizontal plane while the record is being played. The tone arm may also be swung upwardly to change the needle or for any other purpose, in which case the tone arm swings about a horizontal axis extending through the center of curvature of bearing surface 24, the screws 27 not binding when the tone arm is lifted since the center about which the surface 24 is formed is below the bearing formed by the engagement of surfaces 24 and 22. The tone arm and sound box will, of course, be held against rocking from side to side by the engagement of screws 27 with the upper edge of chase 25. A stop may, of course, be provided in chase 25, if desired, to engage one of the screws 27 and thus limit the range of horizontal swinging movement by the tone arm. The joint so formed will be substantially air tight.

When the cover is to be closed the tone arm should be secured in a fixed position to the cover. This may readily be accomplished by the provision of a spring clip 28 secured to the cover, and having a depression therein or hole therethrough. Sound box 13 is provided with a lug 29 which is adapted to engage in this hole or depression when the tone arm is swung into the position shown in dotted lines in Fig. 3, lug 29 wiping past the edge of the spring member 28 and seating itself in the hole or depression therein, referred to. When a record is to be changed the arm 15 may be swung into the latched position described or the lug 29 may be simply positioned on top of clip 28.

Casing 1 is preferably provided with a

space or compartment at its end opposite from that at which the motor and turn table are mounted, in which space records may be stored. When cover 8 is to be closed turn table 5 may be removed from its position on spindle 7 and placed on top of the records in the compartment at the left, as is indicated in dotted lines in Figs. 1 and 3. The records and turn table may, of course, be 10 suitably secured in this position when the machine is to be transported. When the turn table has been thus removed from its operative position ample room will be provided for the tone arm and sound box without 15 in the cover when the latter is closed.

The invention may, of course, take a number of forms, as will be readily understood. In Fig. 6 I have illustrated a casing 1¹ in which the air chamber 11¹ is formed at the 20 under side of the horizontal member 30 of the casing. In this case the motor 3¹ is carried beneath supporting member 30 with the turn table 5¹ above the same, the sound 25 box 13 being carried by a tone arm or connecting arm 15¹ the opposite end of which is provided with a suitable pivoting connection (which may be similar to that described above) with the bracket 20¹ mounted on top of member 30. In this case, of course, member 30 is provided with an opening 31 there- 30 through, by which connection is made from the interior of the tone arm to the thin horizontal air chamber 11¹. The bottom of the air chamber is covered by a membrane 12¹. The casing 1¹ may be closed by a suitable cover 32 which may be closed while the device is being operated.

It will, of course, be obvious that the device may take various other forms. The 40 large diaphragm 12 may be suitably decorated and mounted in a frame in the same manner as a picture, the frame being secured to a wall separating a room from a closet in which the phonograph mechanism 45 may be placed so that scratching and other undesirable noises may be rendered less audible to the listener in the room.

It should be understood that the invention is not limited strictly to the details of construction as described, but is as broad as is 50 indicated by the accompanying claims.

What I claim is:—

1. In a phonograph, the combination of a member having a substantially rectangular sound amplifying chamber, a resilient diaphragm covering said chamber and forming one side thereof, a sound box, and a tone arm providing a direct pneumatic connection between the diaphragm of said sound box and

said resilient diaphragm, said chamber and tone arm forming a substantially air-tight 60 enclosure, the walls of said chamber other than said resilient diaphragm being substantially non-resilient, and said resilient diaphragm being many times larger than the diaphragm of said sound box. 65

2. In a phonograph, the combination of a member having a substantially rectangular sound-amplifying chamber, one of the side walls of which is formed of resilient material and the remaining walls of which are 70 formed of comparatively non-resilient material, the distance between said side walls being slight in comparison with the surface dimensions of said resilient side, a sound box, and a tone arm connecting said sound 75 box and chamber, said sound box, tone arm and chamber forming a substantially air tight enclosure.

3. In a phonograph, the combination of a casing providing a rotatable record support, 80 a cover hinged to said casing, having a shallow rectangular recess formed therein, a diaphragm covering one side of said recess, a sound box, and a tone arm connecting said sound box and recess, said sound box, tone 85 arm and recess forming a substantially air-tight enclosure.

4. In a phonograph, the combination of a casing providing a rotatable record support, a cover hinged to said casing, having a shallow 90 rectangular recess formed therein, a flexible diaphragm covering said recess, a sound box, a hollow bracket secured to said cover with its interior communicating with said recess, and a sound conduit carrying 95 said sound box and communicating therewith and movably connected to said bracket, said sound box, conduit, hollow bracket and recess forming a substantially air tight enclosure. 100

5. In a phonograph, the combination of a casing providing a rotatable record support, a cover hinged to said casing, having a shallow recess substantially rectangular in outline formed therein, a flexible diaphragm 105 covering the opening of said recess, a sound box having a stylus adapted to track a record carried by said record support, and means movably connected with said cover to afford a sound passage extending from said sound box and to the portion of said recess which is lowermost when said cover is open. 110

Signed at New York, in the county of New York and State of New York, this 8th day of July, A. D. 1921.

ROBERT Y. BARROWS.
